UNITED STATES PATENT OFFICE

2,042,912

MACHINE FOR MAKING BINDING STRIPS

William Stuebing, Jr., Cincinnati, Ohio

Application June 13, 1934, Serial No. 730,432
Renewed October 28, 1935

14 Claims. (Cl. 153—1)

This invention relates to machines for making binding strips for calendars, display cards, and the like. More specifically the invention relates to a machine for cutting a strip from a sheet of metal and folding it to the form of a V-shaped trough having relatively wide and narrow sides; forming an eyelet from a metal tape; and subsequently fastening the eyelet to the wider side of the metal strip so as to form the strip and eyelet into an integral binding member.

A binding strip of the above character forms the subject matter of United States Patent No. 1,906,024.

United States patent to William Stuebing, Sr., No. 1,057,295 shows a machine for mounting metal strips on the edges of cards, calendars, etc. The present invention is an improvement upon the machine of Patent No. 1,057,295.

One object of the present improvement is to provide means for indenting or embossing the metal strips so that when a number of the strips are nested together their wider sides will be separated slightly by the indentations. This lessens the tendency of the nested strips to cling together. Another object is to provide means for fastening the eyelet to the strip. A further object is to provide means for nesting the finished strips and subsequently delivering them in nested form to a magazine hopper or other receptacle. Another object is to provide a completely automatic machine for performing all of the above functions. Other objects will be in part obvious and in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings in which is shown one of the various possible embodiments of my invention:

Fig. 1 is a front elevation of the machine with the frame legs cut away and the feeding mechanism for the eyelet tape removed;

Fig. 2 is a plan and horizontal sectional view, the section being taken on line 2—2 of Fig. 4;

Fig. 3 is a horizontal section taken on line 3—3 of Fig. 4;

Fig. 4 is a vertical section taken on line 4—4 of Fig. 2;

Fig. 5 is a side elevation of a part of the machine showing some of the operating mechanism;

Fig. 6 is an isometric view of a metal strip with

the eyelet in position to be fastened to the wider side of the trough;

Fig. 7 is a similar view showing clinching fins struck up from the metal of the strip and eyelet;

Fig. 8 is a similar view showing the fins clinched to fasten the strip and eyelet together;

Fig. 9 is a section on line 9—9 of Fig. 6, showing the indentation;

Fig. 10 is an end view of a plurality of binding strips without eyelets, in nested formation; 10

Fig. 11 is a similar view of a plurality of binding strips with eyelets, in nested formation;

Fig. 12 is an enlarged fragmentary section showing the devices that cooperate to unite an eyelet with its binding strip, the parts being 15 shown at a stage of operation next succeeding that shown in Fig. 4; and

Figs. 13 and 14 are similar views showing the same parts in succeeding stages of operation.

Similar reference characters refer to similar 20 parts throughout the various views of the drawings.

The machine comprises metal sheet feeding mechanism; a strip cutting and folding device and its operating mechanism; a strip indenting 25 device and its operating mechanism; a pusher for feeding the cut strip to the device for indenting and folding, and its operating mechanism; a strip delivery device and its operating mechanism; a second strip pusher or feeding de- 30 vice and its operating mechanism; a movable strip-receiving table and its operating mechanism; eyelet tape feeding mechanism; an eyelet punch and die unit and its operating mechanism; a pressure bar and its operating mechanism; a fin 35 punching device and its operating mechanism; a fin clinching device and its operating mechanism; means and mechanism for delivering the finished strips from the machine in nested formation; and main driving and control mecha- 40 nisms.

The above mentioned devices and mechanisms are all supported in a frame comprising side-frame leg members 10 and supporting upper side-frame members 11. The said frame members are 45 connected together by means of a lower transverse frame-plate 12 and upper transverse frame-plates 13 and 13'. Plate 13 provides an upper surface for supporting the metal sheet 14 as it is fed to the strip cutting and folding mech- 50 anism. Plate 13 also supplies a lower surface supporting a block 15. Similarly plate 13' supports a block 16. The block 16 is movable toward the block 15 to adjust the gap therebetween by means of adjustment screws 17 mounted 55

in the plate 13' and adjustable from the front of the machine.

The drive and control mechanism comprises a cam shaft 18 and an eccentric shaft 19, both extending across the machine and rotatively mounted in the side-frames. The cam shaft 18 may be driven by any suitable mechanism such as by spur gear 20, see Figs. 1 and 3, which may engage gearing upon a drive shaft operated by 10 a motor or in any other suitable manner. Such drive shaft and motor are not shown herein, but equivalent driving mechanism is disclosed in Stuebing Patent No. 1,057,295. Shaft 18 carries a spur gear 21 (see Figs 1 and 3), which meshes 15 with a spur gear 22 rigidly mounted upon the eccentric shaft 19. Thus these two shafts receive their motion from the main driving mechanism. Adjustable connecting rods 23 extend from the 20 ends of the eccentric shaft 19 to the sheet cutting and folding bar 24. This folding bar extends across the machine and slides up and down in guideways 25 formed in the upper side frames, and is shaped as shown in Figs. 1, 2, and 4. It is provided with a sheet cutting knife 26 and 25 folding blade 27. The knife 26 cooperates with a lower knife 28 rigidly supported upon the cross-member 13, the two knives serving as a shear to sever a metal strip 29 from the metal sheet 14.

The metal sheet 14 is advanced toward the 30 front of the machine by sheet feeding devices, herein not shown but fully disclosed in Patent No. 1,057,295, until the advancing edge engages a gauge plate 30 which is adjustably mounted in the folding bar 24 by means of adjustable screws 31. The cut strip 29 falls upon the block 15. The folding bar 24, after this first strip is cut, rises and then again descends, but during the ascent of the folding bar pusher fingers 32 are moved forwardly and push the cut strip over the 40 gap between members 15 and 16 until the strip engages an adjustable gauge plate 33 mounted upon the block 16. In this position the strip is held by the pusher fingers 32 until operated upon first to produce therein the indentations 34, see Fig. 9, and then is folded by the folding blade 27 upon the next descent of the folding bar 24.

The pusher fingers 32 are connected by means of links 35 to the upper ends of arms 36 mounted 50 upon a rock shaft 38. There are two of these pusher fingers 32 symmetrically disposed upon either side of the center line of the machine, each connected to a rock arm 36. The rock shaft 38 has bearings in the side-frames and carries an 55 arm 39 having a roller 40 riding upon a cam 41 on the cam shaft 19. The arm 39 has a rearward extension 42 connected by means of a spring 43 with the frame of the machine. This spring causes the cam roller to follow the contour of 60 the cam 41. Thus the movement of the pusher fingers is coordinated with the movement of the folding bar 24.

In the upper side-frames there is also rotatably mounted a rock shaft 44 which carries a pair of embossing arms 45. These arms have pin-shaped or cone-shaped noses 46 which are adapted to form the indentations 34 in the metal strip, when the said arms 32 are rocked into engagement with the metal strip forcing the metal 70 downwardly into cooperating recesses 47 formed in the upper face of the block 16. The shaft 44 is rocked by an arm 48, see Figs. 1, 2, and 4, which is connected to a cam link 49. A roller 50 carried by the cam link 49 rides in contact 75 with a cam 51 also mounted on the eccentric

shaft 19. Immediately after the embossing arms have indented the strip the folding bar 24 makes its next downward movement and the folding blade 27 engaging the strip 29 forces it downwardly in the gap between blocks 15 and 16 folding 5 the strip and giving it its V-shaped form.

During this movement the pusher fingers releases the strip and move backward into their rear position ready to carry forward the next strip cut off. The blade 27 forces the folded 10 strip through the gap and lets it fall into the V-shaped ends 52 of delivery fingers 53. The fingers 53 now move forwardly and downwardly and lay the folded strip upon the movable table 54 in a position from which the strip may be 15 pushed by the lower pusher fingers 55 to the point where the strip is united with an eyelet.

Delivery fingers 53 are fastened to a rock shaft 56 which extends across the machine and is operated by means shown in Fig. 5. As seen in that 20 view the shaft 56 carries a toothed segment 57 meshing with a toothed segment 58 carried by one arm of a segment lever 59. The segment lever is mounted upon a stud 60 carried by a side-frame and the segment lever is provided with a 25 rearwardly extending arm supporting a cam roller 61 adapted to ride upon a cam 62 mounted upon cam shaft 18. A spring 63 holds the roller 61 against the cam. The delivery fingers 53 are thus rocked by action of the cam from the raised 30 position shown in Fig. 4 where their V ends underlie the folding blade 27, to a lowered position where they deliver the metal strip to the movable table 54. This table 54 is slidably mounted upon the cross-plate 12 and is moved 35 toward and away from the front of the machine by a toggle mechanism composed of parts 64 and 65 connected together by a pin 66 upon which a cam roller 67 is rotatably mounted. The said roller rides in contact with the cam 68 mounted 40 upon the cam shaft 18. There are two of these toggle members, one on each side of the center of the machine, which together produce reciprocation of the table 54. Toggle members 64 are connected to the table 54 by means of pins 69 and 45 the toggle members 65 are connected to suitable supports 70 carried by the plate 12 by means of pins 71.

Seated upon the cross-plate 12 in front of the sliding table 54 is a cross-member 72 in which is 50 seated the punch and die unit 73. Securely mounted in the cross-member 72 are a pair of guide rods 74 which extend above the cross-member to serve as guides for the pressure plate 75 and below the cross-member 72 to serve as 55 guides for the reciprocating punch holder 76. These guides are notched as at 77, Fig. 4, to provide a stop for the advancing edge of the folded metal strip 29 as it is pushed toward the front of the machine by the pusher fingers 55. These 60 pusher fingers, best shown in Figs. 2 and 4, project forwardly from a pusher plate 78 slidably mounted upon the table 54. This plate is connected by means of rearward extensions 79 and links 80 to the upper ends of rock levers 81 65 mounted respectively just inside the side-frame members on either side of the machine upon studs 82. The lower ends of these levers carry cam rollers 83 maintained by means of springs 85 in engagement with cams 84 mounted on cam 70 shaft 18. The cams serve to advance the metal strip and then are withdrawn and substantially simultaneously the eyelet tape 86 is fed rearwardly across the upper surface of the transverse member 72 and die and punch unit block 75

73 until the end of the tape engages the upstanding narrow side of the metal strip. In this position the eyelet tape overlies the wider side of the folded metal strip and an eyelet member 37 5 is ready to be cut off from the tape and secured to the metal strip. As soon as the parts are in the position described, see Fig. 4, the pressure plate 75 descends and resiliently holds the strip and eyelet in proper juxtaposition. The means 10 for operating the pressure plate will be described later.

The punch and die unit is similar to that described in the above-mentioned Patent No. 1,057,295. In the die block 73 are slidably 15 mounted the rods 87 to upper ends of which is affixed the reciprocating die member 88 which is provided with a downwardly extending semi-circular shaped cut-off knife 89 and a round punch 90. In the unit block 73 is a semi-circular shaped die 91 which meshes with the cut-off 20 knife 89 and forms therewith a shear for cutting off the eyelet from the tape. Also in the die block 73 is a die 92 which meshes with the punch 90 constituting a circular punch and die for 25 punching out a round hole in the eyelet tape. It will be obvious that the hole is punched in the tape one step before the tape is advanced to overlapping engagement with the metal strip and that when the cut-off knife operates to cut the 30 eyelet from the tape the eye has already been formed in the eyelet.

An oscillating bail member 93 connected to rock with a rock shaft 94 is provided with a lug 95 to which is pivotally secured a link 96 pivotally 35 connected at its upper end to a plate 97 which unites the lower ends of the reciprocating rods 87. The rock shaft 94 is oscillated by means of a cam 98 mounted upon shaft 18. This cam rocks shaft 94 by means of a cam roller 99 carried at the end of an arm 100 which is fastened to the shaft 94. Thus as the shaft 18 revolves motion is imparted to the rock shaft 94 and swinging bail 93 giving first a downward action to the die member 88 to cause it to operate as a punch 40 and cut-off and then causing the die 88 to rise and release the eyelet and tape.

Slidably mounted in the cross-member 72 are 50 a pair of punches 101 having chisel-like points at their upper ends for piercing the metal strip and overlying eyelet and striking up from both of these parts metal fins, clearly shown in Fig. 7. These metal fins are subsequently clinched or riveted by means of a pair of hammer pins 103 which reciprocate in the pressure plate 75 and 55 strike a hammer blow upon the upturned fins. While these operations of punching the fins and clinching the same are being carried on the pressure plate 75 rests with resilient force upon the superposed strip and eyelet, holding them in position. The fin punches 101 are adjustably seated in the punch block 76 where they are held in place by means of screws 104.

The punch block 76 is made to move up and down in timed relation to the other movable parts of the machine through a connection with the swinging bail member 93. This connection, see Fig. 1, comprises a lever 105 pivotally supported between its ends by links 106 themselves pivotally connected to a lug 107 extending downwardly from the crossplate 12. At one end the lever 105 is pivotally connected by means of a clevis member 108 to the fin punch block 76 and at the other end the lever 105 is pivotally connected by means of a clevis connection 109 with the said bail 93. Thus as the bail rocks to op-

erate the punch and die member 88 it also operates the fin punches 101. It will be noted that the pressure plate 75 is provided with vertical passages therethrough, as more clearly shown in Figs. 12, 13, and 14. These passages, numbered 5 110, serve not only to guide the hammer pins 103 but also serve as clearances for the upwardly operating punch rods 101 as they pass through the metal strip and overlying eyelet, thus enabling the punches to raise the fins to the position 10 shown in Fig. 7.

The mechanism for operating the pressure plate 75 and operating the hammer pins 103 will best be understood by reference to Figs. 1 and 4. On the cutting and folding bar 24 is positioned 15 a bracket 111 provided with an upper guide and bearing member 112 and a lower guide and bearing member 113. Fastened in the bearings 112 are a pair of pressure rods 114. These rods pass slidably through guide member 113 and carry adjacent their lower ends a pressure bar 115 which is adjustably secured to the rods by set screws 116. Beneath pressure bar 115 and between it and the pressure plate 75 are disposed compression springs 117. These springs surround the 20 lower ends of rods 114 and the upper ends of rods 74. Small springs 118 interposed between the lower side of pressure plate 75 and the upper face of cross-member 72 serve to hold the pressure plate normally in the position shown in 25 Figs. 1 and 4. A hammer rod 119 is slidably mounted in guide members 112 and 113 and is provided with a shoulder as indicated at 120. This shoulder supports a spring plate 121 which is guided by pressure rods 114. A hammer 30 spring 122 surrounds the hammer rod 119 and is interposed between the spring plate 121 and the guide block 112. Beneath the lower end of hammer rod 119 is positioned a hammer plate 123 to which are secured the upper ends of the hammer pins 103. A spring 124 is interposed between hammer plate 123 and the upper side of pressure plate 75 in order to hold the hammer plate in the raised position shown in Figs. 1 and 4. 35

On the forward edge of the upper transverse 40 plate 13' is fastened a bracket 125 in which I have pivotally mounted a trigger 126, best seen in Fig. 4. To the upper end of the trigger is secured a spring 127 the other end of which is secured to bracket 125. A hook 128 is formed 45 on the other end of the trigger and spring 127 serves to hold this hook in engagement with a notch 129 formed in the hammer rod 119. The pressure bar 115 is beveled at its rear side and this bevel in the downward descent of the pressure bar engages the rounded nose of an adjustable screw 130 mounted in the trigger. The trigger also carries a spring retainer 131 for gripping and holding the upper ends of flat springs 132. As stated above, the folding bar 24 has an 50 up-and-down motion. As this bar carries the bracket 111, as the folding bar descends, the pressure rods 114 are moved downwardly compressing springs 117 to force the pressure plate 75 downwardly against the work in opposition 55 to the small springs 118. While the parts are held in this position the punches 101 operate to strike up the fins from the metal of the strip and eyelet, while the pressure rods 114 continue to descend further compressing springs 117 until 60 the trigger is released from the notch 129 by engagement with the screw 130 of the pressure bar 115. As soon as the trigger releases the hammer rod 119, the hammer spring 122 which has been compressed during the descent of the guide block 75,

112 imparts a sudden downward movement to the hammer rod which striking hammer plate 123 causes the hammer pins 103 rapidly to descend and strike a hammer blow upon the struck-up fins. This clinches the fins and securely fastens the eyelet to the metal strip so that the finished product is a substantially unit structure. As the trigger is swung about its pivot by the pressure bar 115, the flat springs 132, which at 10 their lower ends are stopped in their rearward movement by the upturned edge of the V-metal strip, are put under a slight tension, for a purpose hereinafter to be described.

Figs. 12, 13, and 14 show the correlated action 15 of the pressure plate 75, the hammer mechanism comprising the hammer rod 119 and the hammer plate 123 with its depending hammer pins 103 and also the action of the trigger 126 and the fin punches 101. Fig. 4 shows all these parts in 20 their normal unoperated position. In Fig. 12 the pressure plate has descended to clamp the eyelet in engagement with the wide side of the metal strip. In this figure the punches 101 have not yet operated nor has the hammer rod 119 been 25 released by the trigger. In Fig. 13 the hammer rod is about to be released by the trigger and the fin punches 101 have been raised to strike up the fins upon the metal strip and eyelet. Fig. 14 shows the parts in the final stage. Here the 30 trigger is held back by the pressure bar 115, the fin punches have descended out of the way of the hammer pins 103 which have been given a hammer blow to clinch the fins, thus riveting the parts together to form the completed strip, 35 disclosed in Fig. 8.

As the binding strips are finished, each one is 40 removed from the position it occupies in Fig. 4 as follows: By this time the movable table 54 has been drawn back by the toggle and cam 68 causing a gap to exist between the forward edge 45 of the table and the die block 72. The pusher fingers 55 have also been withdrawn from contact with the metal strip. As soon, therefore, as the pressure of the pressure plate 75 is removed from the finished binding strip the flat 50 springs 132 which, as described, have been put under tension by the movement of the trigger, react to flip the finished binding strip through the said gap where it falls into the mouth of a hopper 133. This hopper comprises a lower 55 frame or slide member 134, which is secured at its upper end to the cross-member 72 and an upper guide or frame member 135 which is fastened to the transverse frame member 12. As the strips descend the hopper they are held substantially parallel to one another, each in a horizontal position. The strips slide down the hopper member 134 until their advance is stopped by contact with flat springs 136. These springs 60 are fastened to brackets 137 which are in turn supported by the transverse frame members 12 at the rear of the machine, Figs. 2 and 4.

In order to deliver the finished strips in nested 65 formation as shown in Figs. 10 and 11, there is provided a lever comprising a cross-member 138 and a pair of spaced delivery fingers 139. At 70 their upper ends the fingers 139 are fulcrumed in bearings 140 from the frame-plate 12. Lever 138 carries a roller 141 operating on cam 142. This cam is mounted upon rock shaft 94. A 75 spring 143 causes the roller to follow the cam. Slots 144 are formed in the lower hopper member 134 to allow the ends of the delivery fingers 139 to pass below the plane of the said member 134. As the V strip passes down the hopper 133

in contact with the side 134, the delivery fingers 139 are in the position shown in dot and dash in Fig. 4. This allows the V strip to pass under the lever fingers and bear against flat springs 136. The rock shaft 94 now oscillates and cam 142, bearing against roller 141, forces lever 138 rearwardly, thus pressing the binding strips beneath the flat springs 136 to a predetermined point. Each succeeding strip is stopped at this said point and then as the next succeeding strip reaches the point all of the strips which have preceded are pushed rearwardly in the machine along the hopper member 134 until they reach the end of said member where they may be received in any suitable receptacle. Thence they 15 may be removed from time to time from the machine in their nested condition.

The tape 86 from which the eyelets 37 are formed is fed from a suitable roll, not shown, and passes between feed rollers 145 and 146. These 20 rollers are carried by shafts 147 and 148. The shaft 147 and its roller 145 are adjustable against the roller 146 and, by means of a spring 149, the roller 145 is held in contact with the surface of the roller 146 with the proper degree of pressure. 25 The said shafts 147 and 148 are supported in a bracket 150 which is secured at the front of the machine to the cross-plate. Shaft 148 extends laterally beyond the side of the machine and is supported by bracket 151. Beyond the bracket 30 151 a ratchet wheel 152 is fastened to shaft 148. Also mounted pivotally on shaft 148 and adjacent to the ratchet 152 is a lever 153 which at its upper end carries a pawl 154 in position to mesh with the teeth of the ratchet wheel. At its lower end 35 lever 153 is pivotally connected to a cam link 155 which extends rearwardly and has a forked end 156 engaging cam shaft 18, as shown in Figures 3 and 4. Roller 157 carried by the link 155 in contact with a cam 158 formed on shaft 18 serves, 40 as the shaft 18 rotates, to rock the lever 153 and cause the ratchet pawl 154 to advance the ratchet wheel one notch at each revolution of the shaft. This timing of the ratchet co-ordinates with the other parts of the machine so as to feed the tape 45 to the pressure plate to furnish an eyelet for each folded strip received beneath the pressure plate.

The operation of the various instrumentalities of the machine have been described in detail. A brief resumé connecting together these separate 50 operations will tend to make clearer the operation of the machine as a whole. It should be understood then that a sheet of metal 14 and an eyelet tape 86 are both fed into the machine at the same time. The metal plate has sheared there- 55 from a flat metal strip 29 each time the cutting and folding bar 24 descends. After each strip has been cut off, while the folding head rises, the cut-off strip is moved by the pusher fingers 32 against the gauge plate 33 and while held between these 60 parts is indented by the members 45 rocking upon the rock shaft 44. The folding blade 27 is then brought down to fold the strip and deliver it to the delivery fingers 53. In its passage to the de- 65 livery fingers the strip is guided by a guide member 159. Upon being received by the fingers 53, these are rocked forward to deliver the folded strip upon the table 54 which at this time occupies a position closing the hopper 133. The pusher fingers 55 then advance the folded strip to the 70 position shown in Fig. 4, where the forward edge is stopped by the notched portion 77 of guide rods 74. While this has been taking place the eye of an eyelet 37 has been punched by the die punch 90, the metal tape 86 has then been ad- 75

vanced beyond the die punch 90 by means of the ratchet mechanism until the end of the tape comes in contact with the upturned side of the metal strip. The pressure plate is now operated to hold 5 the strip and eyelet tape together while the die 88 descends to cut the eyelet 37 free from the tape 86.

While still held in its proper position by pressure plate 75 the fin punches 101 rise and strike 10 up fins from the two plies of metal which lie together. These punches then retreat and a blow is struck upon the hammer pins 103 causing them to clinch the fins, thus uniting the metal strip and eyelet member. Then, as the table 54 and 15 the pusher fingers 55 have been moved out of the way, opening the mouth of the hopper 133, upon the ascent of the pressure plate 75, the tensioned springs 132 flip the finished binding strip into the hopper 133 where it is delivered by means 20 of the delivery fingers 139 beneath the spring 136 to take its place at the rear end of the row of nested strips which have preceded it. The removal of the nested strips from the machine may be accomplished in any desired manner.

25 It will be seen from the foregoing that this invention provides a machine having devices and mechanisms for accomplishing automatically all of the aims and objects hereinbefore set forth in a simple and efficient manner. Each of the instrumentalities employed is simple in structure and simple in its operative connection with the driving mechanism of the machine. The various operating mechanisms for the different instrumentalities are so co-ordinated as to their times of 30 operation that each step takes place in its regular order. Thus, one after the other the folded strips and punctured eyelets are made, brought together, united and then delivered from the machine in nested formation.

40 As many possible embodiments may be made of the above invention without departing from the scope thereof, it is to be understood that all matter herein set forth or shown in the accompanying drawings is to be interpreted as illustrative and not in a limiting sense.

I claim:

1. In a machine of the character described, in combination, a hopper, a movable table, means for periodically moving said table alternately to close and open the mouth of said hopper, means for successively feeding folded metal strips across said table to a position beyond the mouth of said hopper, means periodically operative in the said position of said strips to perform a finishing operation thereon, and means responsive to the operation of said finishing means for delivering said strips into the open mouth of said hopper when the finishing operation has been completed.

60 2. In a machine of the character described, in combination, a hopper, a movable table, means for periodically moving said table alternately to close and open the mouth of said hopper, means for successively feeding folded metal strips across said table to a position beyond the mouth of said hopper, means periodically operative in the said position of said strips to perform a finishing operation thereon, means responsive to the operation of said finishing means for delivering said strips into the open mouth of said hopper when the finishing operation has been completed, and means acting successively on said strips as they pass through said hopper for collecting them and discharging them from the machine in nested formation.

70 3. In a machine of the character described, in

combination, a hopper, a movable table, means for periodically moving said table alternately to close and open the mouth of said hopper, means for successively feeding folded metal strips across said table to a position beyond the mouth of said hopper, means for indenting a portion of each of said strips before it is acted upon by said feeding means, means periodically operative in the said position of said strips to perform a finishing operation thereon, and means responsive to the operation of said finishing means for delivering said strips into the open mouth of said hopper when the finishing operation has been completed. 5

4. In apparatus of the character described, in combination, a hopper, means for successively feeding unfinished articles to a finishing position adjacent the mouth of said hopper, means periodically operative in the said position of said articles to perform a finishing operation thereon, 10 and means responsive to the operation of said finishing means for delivering said articles into the mouth of said hopper when the finishing operation has been completed. 15

5. In apparatus of the character described, in combination, a hopper, means for successively feeding unfinished articles to a finishing position adjacent the mouth of said hopper, means periodically operative in the said position of said articles to perform a finishing operation thereon, 20 means brought into action responsive to the operation of said finishing means at the end of the finishing operation for delivering said articles into the mouth of said hopper, and means acting successively on said articles as they pass through 25 said hopper to collect them and discharge them 30 from the machine in compact formation. 35

6. In apparatus of the character described, in combination, a movable pressure plate, means for successively feeding folded metal strip members 40 beneath said pressure plate, means for successively feeding metal eyelet members beneath said pressure plate in overlapping relation to said strip members, means for automatically causing said pressure plate to engage said overlapping 45 members, means for automatically punching and striking up portions of said overlapping members, and means for automatically clinching said struck-up portions. 50

7. In apparatus of the character described, in combination, a movable pressure plate, means for successively feeding folded metal strip members beneath said pressure plate, means for successively feeding metal eyelet members beneath said pressure plate in overlapping relation to said strip 55 members, means for causing said pressure plate to engage said overlapping members, means for punching and striking up portions of said overlapping members, and means for clinching said struck-up portions. 60

8. In apparatus of the character described, in combination, a movable pressure plate, means for successively feeding folded metal strip members beneath said pressure plate, means acting in advance of said feeding means for forming indentations at predetermined points along said strip members, means for successively feeding metal eyelet members beneath said pressure plate in overlapping relation to said strip members, means for automatically causing said pressure plate to engage said overlapping members, means for automatically punching and striking up portions of said overlapping members, and means for automatically clinching said struck-up portions. 65 70 75

9. In a machine of the character described, in combination, a horizontal support for a plurality of overlapping plies of metal, a pressure plate movable downwardly toward said support to hold said plies in operative position, punching means slidable in said support adapted to cooperate with an opening in said pressure plate to form on said overlapping plies coacting clinching members, hammer means movable upwardly and downwardly in said pressure plate, and means responsive to the downward movement of said pressure plate for causing said hammer means to strike and clinch said clinching members.
10. In a machine of the character described, in combination, a horizontal support for a plurality of overlapping plies of metal, a pressure plate movable downwardly toward said support to hold said plies in operative position, punching means slidable in said support adapted to cooperate with an opening in said pressure plate to form on said overlapping plies coacting clinching members, hammer means movable upwardly and downwardly in said pressure plate, means responsive to the downward movement of said pressure plate for causing said hammer means to strike and clinch said clinching members, and means for operating said pressure plate, punching means and hammer means in a predetermined timed relation.
11. In apparatus of the character described, in combination, a hopper, means for successively feeding unfinished articles to a finishing position adjacent the mouth of said hopper, means periodically operative in the said position of said articles to perform a finishing operation thereon, means operative at the end of each finishing operation for successively delivering said articles into the mouth of said hopper, and means acting successively on said strips as they pass through the hopper for collecting them and discharging them from the machine in nested formation.
12. In apparatus of the character described, in combination, movable holding means, means for successively feeding strip members into operative relation to said holding means, means for successively feeding other members to said holding means in overlapping relation to said strip members, means for causing said holding means to engage said overlapping members, means for punching and striking up portions of said overlapping members, and means for clinching said struck-up portions.
13. In apparatus of the character described, in combination, movable holding means, means for successively feeding strip members into operative relation to said holding means, means for successively feeding other members to said holding means in overlapping relation to said strip members, means for causing said holding means to engage said overlapping members, means for punching and striking up portions of one of said overlapping members, and means for upsetting said struck-up portions in a manner adapted to fasten said members together.
14. In apparatus of the character described, in combination, means for automatically feeding a plurality of folded metal strips and a plurality of tab members one by one into juxtaposition, means for automatically fastening together each pair of juxtaposed members, and means for automatically delivering a plurality of united pairs of members in nested form ready for packing.

WILLIAM STUEBING, JR.
